UNITED STATES PATENT OFFICE.

WILLIAM H. JONES, OF FELLOWS, AND ANTON EBERLE, OF TAFT, CALIFORNIA.

BALL CATCHER.

Application filed June 22, 1926. Serial No. 117,772.

This invention relates to improvements in ball catchers designed to be used upon sucker rods in well pumping. The device is primarily designed to be used in conjunction with the sucker rod couplings disclosed in application Serial No. 82,220, filed January 19, 1926, by William H. Jones.

An object of this invention is to provide a device adapted to be mounted upon the lower end of a sucker rod a short distance above the pump plunger which will catch the broken or loosened balls which may become detached or fall out of the sucker rod couplings disclosed in the above mentioned application.

Another object of this invention is to provide a device of relatively cheap and simple yet durable construction which will catch articles which may fall in a well about the sucker rod and prevent them from reaching the pump, which might cause damage to the pump barrel or plunger.

A further object of this invention is to provide a device which will catch articles falling in a well about a sucker rod preventing them from reaching the pump which will enable the fluid pumped by the pump to readily pass therethrough.

With the foregoing and other objects in view which will be made manifest in the following detailed description and specifically pointed out in the appended claim, reference is had to the accompanying drawings for an illustrative embodiment of the invention, wherein—

Figure 1 is a sectional view through a pump tube illustrating the improved ball catcher in applied position therein,

Fig. 2 is a top plan view of the ball catcher, and

Fig. 3 is a vertical section taken on the line 3—3 of Fig. 2.

Referring to the accompanying drawings wherein similar reference characters designate similar parts throughout, the pump tube is indicated at 10, in which there is located the conventional pump plunger 11 adapted to be reciprocated by a sucker rod 12. The couplings for the sucker rod as disclosed in the above mentioned application have vertical grooves 13 provided thereon, in which a plurality of balls are disposed. The balls 14 on engagement with the interior of the pump tube 10 form an anti-friction bearing, which reduces the friction between the couplings for the sucker

rod sections and the pump tube. They also serve to prevent the pump tube 10 from being worn through by the sucker rod couplings, and furthermore prevent the sucker rod couplings from becoming worn, thus preventing the sucker rod sections from separating while in the well hole.

The improved device is indicated generally at 15 and is in the form of a rod 16 preferably threaded at both ends, so that it may be readily attached to the sucker rod as by couplings 17 at the bottom of the sucker rod. It consists of an open topped cup 18 through which the rod 16 extends, the rod being threaded through the bottom 19 of the cup, as clearly shown upon the drawing, the bottom 19 of the cup is relatively thick so that this bottom can be made the sole means for fastening the cup to the rod, the bottom being relatively thick will firmly hold the cup on the rod and eliminates any bracing of the cup near its top so that the top of the cup is entirely open around the rod. A plurality of apertures 20 are formed in the bottom of the cup providing for the upward passage of fluid therethrough. The sides of the cup are also preferably perforated as indicated at 21, so that the fluid may pass through the perforations into the cup. As clearly shown upon Fig. 1 the external diameter of the cup is slightly smaller than the internal diameter of the pump tube, there being a clearance preferably of about one-eighth inch. In the event that the balls 14 during the reciprocation of the sucker rod should become worn or broken and fall out of their respective grooves 13, these balls or parts thereof on falling within the pump tube about the sucker rod will be caught by the cup and will be prevented from falling on top of the pump plunger 11.

In this manner the improved ball catcher will serve to catch balls or fragments of balls or any other small articles which may fall within the pump tube about the sucker rod and prevent them from falling on top of the pump, which might cause damage to the pump. From the above described construction it will be readily appreciated that the improved ball catcher is of cheap and simple yet durable construction and may be readily applied to a sucker rod. It will, of course, be understood that the use of the improved ball catcher is not limited to the particular sucker rod having the special couplings employed, but it may be used on any

type of sucker rod which is provided with construction which may break or fall down within the pump tube.

It will be understood that various changes may be made in the detail of construction without departing from the spirit or scope of the invention as defined by the appended claim.

We claim:

- 10 In a deep well pump wherein there is a pump tube, a reciprocable plunger and a sucker rod for reciprocating the plunger, a device of the class described comprising a cylindrical cup having a relatively thick bottom, through which there are a plurality of inwardly and upwardly inclined apertures, the walls of the cup being perforated and extending parallel to the walls of the

tube throughout the entire portion of their length, the bottom having a central aperture through which the sucker rod is screwed, the outside diameter of the cup being slightly less than the internal diameter of the pump tube so as to prevent the cup assembly from having frictional engagement with said pump tube, and the cup being located on the sucker rod a short distance above the plunger so as to catch articles falling in the pump tube, said cup being secured to the sucker rod only by its bottom so as to leave its top completely open about the sucker rod.

In testimony whereof we have signed our names to this specification.

WILLIAM H. JONES.
A. EBERLE.
